UNITED STATES PATENT OFFICE.

LESLIE R. N. CARVALHO, OF TOLEDO, OHIO, ASSIGNOR TO THE CLOSURE SERVICE COMPANY, OF TOLEDO, OHIO, A CORPORATION OF OHIO.

BOTTLE CAP.

Application filed June 9, 1924. Serial No. 718,756.

My invention relates to a sheet metal cap designed and adapted to form a closure for bottles or other receptacles. More particularly, it relates to a bottle cap of the two piece type comprising a top piece or "button" formed from one piece of sheet metal, and a flange or "body" formed of a separate piece of sheet metal.

An object of my invention is to provide an improved form of connection between the button and body, by which a strong rigid cap is produced.

A further object is to provide a cap having various advantages from a manufacturing standpoint as compared with caps of this type heretofore in use.

Other objects of the invention will appear hereinafter.

In the accompanying drawings:
20 Figure 1 is a part sectional elevation of a cap constructed in accordance with my invention, and the receptacle to which it is applied.

Figure 2 is a plan view of the blank from 25 which the body of the cap is formed.

Figure 3 is a section at the line III—III on Figure 1.

Figure 4 is a fragmentary sectional view 30 on an enlarged scale, of one corner of the cap.

The cap comprises a top portion or button 5 stamped from a piece of flat sheet metal, and a body 6 formed from a separate blank of sheet metal of the shape shown in Figure 2.

The button 5 is formed with an inner annular bead 7 adjacent its periphery which protrudes downward or inward, and an upwardly projecting outer annular bead 8 at 40 the periphery of said button. The outer wall of the bead 8 is extended downward to form a vertical flange 9. The beads 7 and 8 preferably merge into each other, forming in cross section a compound curve.

The body 6 is formed from the blank, Fig. 2, by uniting its ends 10 and 11 to form 45 an interfolded seam 12. The upper edge of the body 6 is curved inwardly and downwardly to form an annular gripping portion 10 which fits over the bead 8, the lower edge 50 of the part 10 projecting downward into the groove 7. When the parts are assembled, the curved portion 10 is caused to grip the bead 8 and thereby securely unite the parts.

55 It will be noted that with this construction,

there are four thicknesses of metal at the upper peripheral portion of the cap, including the two side walls of the bead 8 and the two side walls of the part 10. In this manner, a strong and rigid construction is produced, 60 permitting the use of comparatively thin sheet metal and thus effecting a substantial economy of material. The downwardly extending flange 9 of the cap adds strength and rigidity to the cap. Said flange extends 65 downward a sufficient distance to cover the notch 13 which is ordinarily formed in the body of the cap at the upper end of the seam 12.

The cap, as herein shown, is applied to a 70 bottle 14, the upper edge or lip 15 of which is substantially the same diameter as the bead 7, so that said lip comes directly beneath and in register with the bead. A liner 16 of cork or other suitable material provides a perfect 75 seal between the bottle and the cap. When the cap is originally applied to the bottle, the lower edge 17 of the cap is flanged or bent inwardly beneath an annular bead 18 formed on the neck of the bottle to thereby hold the 80 cap against displacement. The cap is formed with a weakened line or score 19 which extends circumferentially of the cap and provides a removable strip 20, the end of which is extended to form a finger piece 21.

When it is desired to open the bottle, the strip 20 is torn off, allowing the cap to be removed. After the cap has originally been removed, it serves as a temporary closure for 85 the bottle and can be taken off as often as required in dispensing the contents of the container.

By placing the bead 7 directly over the lip of the container, the pressure with which the cap is originally applied, is applied directly over the bottle lip in a manner to form 90 an effective seal. The beads 7 and 8 also impress the liner and assist in holding it against accidental displacement when the cap is removed from the container.

The sheet metal from which the cap is formed is preferably lacquered on both sides. The raw edge of the button 5 produced in stamping the button from the lacquered metal, is fully protected by the liner 16 105 against exposure to the contents of the container and thus protected against corrosion. The raw edges of the body portion 6 are also hidden from view. The use of an interfolded seam between the button and body por- 110

tion to conceal the raw edges, as has hitherto been considered necessary with this type of cap, is, therefore, entirely unnecessary with the present invention, thereby permitting 5 the use of the construction herein shown with its attendant advantages.

Modifications may be resorted to within the spirit and scope of my invention.

What I claim is:

- 10 1. A cap for a container, comprising a button or top portion and a body portion formed of separate pieces of sheet metal; said button being formed with an inner annular downwardly projected bead adjacent the periphery of the button, and an outer annular bead surrounding and extending upward from said first mentioned bead, the outer wall of said outer bead being extended vertically downward to form a peripheral flange on the button extending into the body portion; said body portion being formed of a strip having its ends united in an inter-folded seam terminating a short distance below the upper edge of said body, the upper 25 edge portion of the body being curved inwardly and downwardly to embrace the outer bead of the button and frictionally hold said top and body portions together, permitting them to be assembled or separated solely by a relative endwise movement.
- 20 2. The combination of a container and a cap therefor, said cap comprising a circular top portion, body portion, and a liner, said top and body formed of separate pieces of sheet material; the top being formed with an inner annular bead projecting downwardly and directly overlying the upper edge or lip of the container, and an outer 25 peripheral bead surrounding and projecting upwardly above said inner bead and ter-

minating in a depending circumferential flange surrounding the upper end of the container and of substantially greater diameter than said end, said liner being seated 45 in the cap and held under compression between the lip of the bottle and said inner bead, said body having its upper edge curved inwardly to embrace said outer bead and frictionally hold said top and body portions 50 together, permitting them to be assembled or separated solely by a relative endwise movement, the neck of said container being formed with an annular rib spaced below the lip of the container, said body of the 55 cap having its lower edge bent inwardly to underlie said rib and thereby secure the cap on the container, the cap being formed with a circumferential score adjacent its lower edge providing a removable strip.

60 3. A cap for a container, comprising a circular top portion and a cylindrical body portion formed of separate pieces of sheet metal, said top portion formed with an upwardly protruding bead extending circumferentially thereof and forming the periphery of said top portion, the outer wall of 65 said bead being extended downwardly to form a peripheral flange telescoping into the upper end of the body portion, said 70 body portion having its upper edge portion curved inwardly and downwardly to embrace said bead and frictionally holding the bead, whereby said top and body portions may be united solely by an endwise movement of the top portion into the body portion and held together by frictional contact.

Signed at Toledo, in the county of Lucas and State of Ohio, this 6th day of June, 1924.

LESLIE R. N. CARVALHO.
